CLAIM

The ornamental design for tyre, as shown and described.

DESCRIPTION

FIG. 1 is a front view of tyre showing our new design;
FIG. 2 is a back view thereof;
FIG. 3 is a left view thereof;
FIG. 4 is a right view thereof;
FIG. 5 is a top view thereof;
FIG. 6 is a bottom view thereof; and,
FIG. 7 is a perspective view thereof.
The broken lines shown in the drawings depict portions of
the tyre that form no part of the claimed design.
